ICHIRO NOZAWA, OF TOKYO, JAPAN.

STEEL OR IRON PILLAR PARTICULARLY ADAPTED FOR MOUNTING ELECTRIC WIRES.

Application filed May 11, 1923. Serial No. 638,372.

This invention relates to steel and iron columns particularly adapted for supporting electric wires. Heretofore it has been customary to use diagonal bracings or truss members on the outer surface of each of the members constituting the column. There is, however, the drawback that while such bracings afford a resistance to an external force acting in a direction parallel to the plane of the bracings, there is nothing to resist an external force acting in a direction normal to the plane of the bracings. It has therefore been necessary to employ a large amount of steel or iron in order to strengthen the column so as to resist external forces in all directions.

The object of this invention is to overcome the above defects by the employment of diagonal bracings which do not lie in the plane of the outer side of each component member, but which are secured to the flanges of the members internally thereof and diagonally within the surface of the members. In this way any desired column can be constructed very economically and at the same time so as to afford much greater strength.

The foregoing and other features are hereinafter referred to, and the invention will now be described with reference to the accompanying drawings in which:

Fig. 1 is a front elevation of a column embodying the present invention.

Fig. 2 is a side elevation thereof.

Fig. 3 is a section on Fig. 1.

Figs. 4, 7 and 10 are each front elevations of modifications of the present invention.

Figs. 5, 8 and 11 are side elevations of Figures 4, 7 and 10 respectively.

Figs. 6, 9 and 12 are sections of Figures 4, 7 and 10 respectively.

Figs. 13, 14, 15 and 16 are diagrammatic views explaining the resistance of the various members to external bending forces.

Figs. 17 and 18 are elevations of typical constructions of the present invention with assembled necessary parts. Fig. 17 being a further modification in which the diagonal members begin intermediately the plane of the transverse pieces and terminate in said plane, while Fig. 18 is the column shown in Fig. 4, but constructed so as to taper toward the top.

As shown in Figs. 1-3, a pair of angle members, of iron or steel, are symmetrically arranged in spaced relation, the flanges thereof being positioned facing each other. The

rear flange b_1 of the member B is joined lower down to the front flange a_1 of member A by a brace c_1 , while the rear flange a_2 of member A is joined lower down to the front flange b_2 of the member B, by a brace c_2 . Both the braces c_1 and c_2 are thus diagonal braces. In the same manner other diagonal braces c_3 are used to interconnect the flanges of the members A and B as shown in the drawings.

The braces are connected to the angles, by any desired means, such as riveting, welding, and the like.

Now assume, in Figs. 13 and 14, that an external force F acts at a point f on the end of a column secured to the ground or any other body, represented by the line G—L. In this case various stresses are brought into play but to simplify the following treatment, only the principal stresses will be taken into consideration.

In Fig. 13, if an external force F acts as indicated, a rectangle $a_0b_0b_3a_3$ formed by the various members is subjected to a strain tending to deform the rectangle into a parallelogram $a_0b_0b_3a_3$ as in Fig. 14. Let us suppose the braces a_1b_0 and a_1b_3 to be in the same vertical plane as the rectangle $a_0b_0b_3a_3$, in which case the diagonal brace b_0a_1 is subjected to a compression force F_1 , while brace a_1b_3 is subjected to a tension F_2 , so that the external force F is resisted by a compression stress in the member A, a tension stress in the member B, a compression stress F_1 in brace a_1b_0 , and a tension, F_2 , in brace a_1b_3 . However, as the diagonal braces a_1b_0 and a_1b_3 are not situated in the same plane as the rectangle $a_0b_0b_3a_3$ in the actual construction, the compression stress F_1 is divided into two components F_0 and F_s at the point a_1 as shown in Figs. 13 and 15. The component F_s thrusts forward on front flange a_1 of the member A and tends to twist the flange forward and at the same time the tension stress F_2 will act at the point a_1 on the diagonal brace a_1b_3 .

The tension stress F_2 is divided into two components, F_5 and F_6 while the component F_5 is balanced by F_s so as to eliminate any torque on flange a_1 . It will therefore be seen that the resistance afforded by the given construction covers tension and compression stresses due to compression member a_1b_0 , tension member a_1b_3 , and the members A and B.

If a force P acts at the point p in a direction opposite to the force F , the rectangle $a_0b_0b_3a_3$ will become deformed in the opposite direction to that above-mentioned to make a

parallelogram. The diagonal brace a_1b_0 then is subjected to tension and other brace a_1b_3 to compression while the members A and B are subjected to tension and compression in opposite directions to those above described.

In this case it is evident that no twisting stress takes place at the point a_1 under the reasoning pointed out in the above example where the force F was assumed to act.

Next, let us assume, in Figs. 15 and 16, an external force W acts forwardly, from the rear, of the members A and B, in which case the bending stress afforded by the members resists the external force W and at the same time the stresses produced by diagonal braces c_1 and c_2 also resist the external force.

Let us consider, in Figure 16, that the external force W is divided into two components w_1 and w_2 acting respectively at the two points a_0, b_0 . The component force w_2 , acts at the point b_0 , and a bending stress is produced due to the component w_2 , to resist the external force W, while at the same time a stress is produced on the diagonal bracing c_1 . If c represents a rear flange having its terminal edge in the same plane as that of the front edge a of the member A, perpendicular to the plane passing through the apices of the angle member and we assume the component force w_2 to act at the apex of a triangle b_0a_1c , it is evident that a compression stress is produced on the side a_1b_0 and a twisting stress on the side a_1c , so that a compression stress is produced to resist the external force W on the diagonal bracing a_1b_0 to strengthen the members A and B.

Again, if d represents a front flange having its terminal edge in the same plane as that of the rear flange b_2 of the member B, perpendicular to the plane passing through the apices of the angle member some component force w_3 of external force W may be assumed to act at the apex a_1 of the triangle a_1db_2 . In this case it will be seen that a tension stress is produced on the side a_1b_2 and a twisting stress on the side b_2d . In other words, a tension stress is produced on the diagonal brace b_2a_1 (previously mentioned as c_2) in opposition to W so as to strengthen the structure of the members A and B.

It should be noted that the component of compression stress produced on the diagonal brace a_1b_0 (previously referred to as c_1) thrusts forwardly on the flange a_1 to produce a twisting stress s. At the same time the tension stress produced on the brace a_1b_2 , gives rise to a twisting stress s_1 acting at a_1 to exert a force thrusting rearwardly on the flange. In short, the forces s and s_1 counteract so as to eliminate twisting. These are the characteristic features of the present invention.

If an external force W_1 acts, instead of the force W in the opposite direction to the latter, it will be seen, in the triangle a_1b_0c , that

in contradistinction to the case of the external force W, a tension stress is produced on the side a_1b_0 or the brace c_1 and a compression stress on the side a_1b_2 or the brace c_2 , so as to strengthen the members A and B.

Furthermore, the horizontal joining members or braces such as ab, a_0b_0 etc., do not afford stresses to resist external force, except in some particular cases where a horizontal component of an external force is to be overcome. This means that horizontal braces do not perform the function of reinforcing the column and particularly to resist external forces W or W_1 .

The group of Figures 4 to 6 inclusive illustrates a construction in which double diagonal braces are shown, lying substantially in a single plane as indicated in Fig. 5, and beginning at a cross piece on one side of the angle member and terminating on an upper or lower cross piece on the opposite side.

In the group of Figures 7 to 9 inclusive, the construction is substantially similar to that shown in Figs. 4 to 6, except that channel irons are used instead of angle irons. In the group of Figures 10 to 12, the diagonal braces begin and terminate, intermediate the planes of the cross pieces, and they are also in the planes of the edges of the angle members which they connect.

Figs. 4 to 6 and 7 to 9 inclusive, show the employment of double diagonal bracings the first named group of figures illustrates a column constructed of V members while Figs. 7 to 9 show the same type of construction of braces, applied to channel members and the construction in each figure is similar to that in Figs. 1, 2 and 3. It should be noted that as the diagonal braces each secure together the flanges of opposite sides of the main members constituting the column, in every figure representing front elevations, side elevations or cross sectional plan views, diagonal braces are situated in diagonal perspective positions, which fact constitutes a novel feature of the invention, affording a resistance to external force of any direction.

Figs. 10, 11 and 12 are modifications of diagonal braces in which one pair, or two pairs, of elongated bars are bent at k^3 , m^4 , m^3 , k^4 and so on in zigzag fashion. In each figure an elongated bar is welded to the flanges at the indicated points, being diagonally positioned on the members K and M.

In these constructions, diagonal braces formed by welding an elongated bar, or bars, to various flanges, are to be used in place of diagonal braces as in Figs. 1, 2 and 3.

In Figs. 17 and 18 a practical application of the invention is shown the column of the former figure being constructed in the same manner as that shown in Fig. 4 but with a slight tapering toward the upper end, Fig. 17 showing a column of the same cross section except that a single system of diagonal brac-

ing is used instead of a system of intersecting braces.

What I claim is:

- 5 1. A support for mounting electric wires, comprising, two angle bars symmetrically positioned vertically and in spaced relation, the flanges thereof being positioned towards each other, a diagonal brace connecting the rear flange of one of the bars to the forward flange of the other bar, and a second diagonal brace connecting the rear flange of the latter bar to the forward flange of the former bar.
- 10 2. A support for mounting electric wires, comprising, two angle bars symmetrically positioned vertically and in spaced relation, the flanges thereof being positioned towards each other, a double diagonal bracing connecting
- 15

the rear flange of one of the bars to the forward flange of the other bar, and a second double diagonal bracing connecting the rear flange of the latter bar to the forward flange of the former bar. 20

3. A support for mounting electric wires, comprising, two angle bars, symmetrically positioned vertically and in spaced relation, the flanges thereof being positioned towards each other, an oblique member connecting the rear flange of one of the bars to the forward flange of the other bar, a second oblique member connecting the rear flange of the latter bar to the forward flange of the former bar. 25 30

Signed at American Embassy, Tokyo, this 17th day of April, A. D. 1923.

ICHIRO NOZAWA.
